LATCHING MECHANISM FOR ELECTRIC
SWITCHES

Theodore B. Jochem, Edwin W. Seeger, and
Palmer T. Severson, Wauwatosa, Wis., assign-
ors to Cutler-Hammer, Inc., Milwaukee, Wis., a
corporation of Delaware

Application January 17, 1945, Serial No. 573,182

4 Claims. (Cl. 200—169)

1

This invention relates to electric switches and more particularly to shock-proof switches of the knife blade type.

The present invention has among its objects to provide a shock-proof knife switch which meets the requirements of navy service, or in other words, a knife switch which remains open or closed when subjected to high shock in any direction.

Another object is to provide a simple, rugged and reliable latching mechanism which can be readily applied to a knife blade switch to hold the same in closed position against the action of shocks or jarring forces to which the switch may be subjected.

Another object is to provide a latching mechanism of the aforesaid type which operates to automatically lock the switch when the same is moved into closed position, and which is releasable by the operating handle of the switch.

Various other objects and advantages of the invention will hereinafter appear.

An embodiment of the invention is illustrated in the accompanying drawing, it being understood that the embodiment illustrated is susceptible of modification without departing from the spirit and scope of the appended claims.

In the drawing,

Figure 1 is a front elevational view of a knife switch embodying the invention;

Fig. 2 is a side view and Fig. 3 is a top view of the switch shown in Fig. 1, and

Fig. 4 is a sectional view on line 4—4 of Fig. 3.

Referring to Figs. 1 and 2, the same illustrate a knife switch including a pair of blades 1—1, each of which has a lower hinge jaw 2 and an upper contact jaw 3 associated therewith. The hinge jaws 2 and contact jaws 3 are mounted upon vertically disposed insulating panel 4, and each of the blades 1 is pivotally secured to its associated hinge jaw 2 by a bolt 5. The free ends of blades 1 are secured to an insulating tie bar 6 which carries an operating handle 7. Tie bar 6 also carries a latch 8 which cooperates with a stationary stop pin 9 to lock blades 1 in engagement with their associated contact jaws 3. As hereinbefore set forth, latch 8 is releasable from pin 9 by rotative movement of handle 7 to permit disengagement of blades 1 from their associated contact jaws 3 and said handle and latch are constructed and arranged to insure against unlocking of the switch under high shock conditions.

More specifically, handle 7 and latch 8 are mounted upon an insulating block 10 which is

secured to the upper side of tie bar 6 by screws 11. Operating handle 7 is mounted between the side arms of a horizontally disposed U-shaped bracket 12 upon a pin 13. The connecting portion 14 of bracket 12 is rotatably supported upon the front face of block 10 by a pivot pin 15 and as shown in Fig. 4 said pin is fixed to said bracket and is rotatably supported and held against axial movement within an opening in block 10. Pivot pin 15 is located midway between the side arms of bracket 12 whereby said bracket and handle 7 are balanced upon said pin.

Latch 8 is disposed at right angles to tie bar 6 and is pivotally supported within a slot formed in the underside of block 10 upon a horizontally disposed pin 16. The rear end of latch 8 is provided with a downwardly extending hook projection 17 for engaging stop pin 9 and the front end thereof projects beyond block 10 for engagement with cam surfaces 18 formed by a V-shaped recess 19 in the under side of the connecting portion 14 of bracket 12. Pivot pin 16 is located so that latch 8 is balanced thereon, and said latch is biased by a spring 20 to maintain the front end thereof in engagement with the cam surfaces 18.

Stop pin 9 is carried by an insulating block 21 which is secured to panel 4 by bolts 22. Block 21 is recessed to receive the rear end of latch 8 and the front end of said block serves as a stop for tie bar 6 to limit inward movement of blades 1 with respect to their associated contact jaws 3.

In connection with the foregoing it will be noted that the front end of latch 8 is held by spring 20 in engagement with the cam surfaces 18 to normally hold bracket 12 and handle 7 in the horizontal position shown in Fig. 1. With handle 7 in this position the hook projection 17 of latch 8 is moved into locking engagement with stop pin 9, as shown in Fig. 2, to lock blades 1 when the same are moved into full engagement with their associated contact jaws 3. As is apparent from Fig. 1, upon rotation of handle 7 in either direction out of its normal horizontal position one or the other of the cam surfaces 18 operates to move the front end of latch 8 downwardly against the action of spring 20. The hook projection 17 is thus moved out of engagement with stop pin 9 to permit opening of the switch by a forward pull on operating handle 7. As hereinbefore set forth, latch 8 is balanced upon its associated pivot pin 16 and handle 7 and bracket 12 are balanced upon their associated pivot pin 15. These parts therefore do not tend

to rotate under the action of accelerating forces caused by shock. Thus when the switch is in closed position as shown in Fig. 2, spring 20 operates to maintain latch 8 in engagement with stop pin 9 and to also prevent movement of handle 7 out of its normal horizontal position to thereby prevent unlocking of the switch under shock conditions.

As shown in Figs. 1 and 2, each of the hinge jaws 3 carries a stop pin 23. These stop pins cooperate with stop surfaces 24 on the lower ends of knife blades 1 to limit opening movement of said blades beyond the dotted line position shown in Fig. 2. It will be noted that the stop pins 23 are located as close as possible to pivot bolts 5 so that forces resulting from shock are transmitted from said stop pins to blades 1 through relatively short lever arms to insure against movement of said blades into circuit closing position under shock conditions.

What we claim as new and desire to secure by Letters Patent is:

1. A shock-proof knife switch comprising a blade element pivoted at one end, a front operating handle mounted upon the free end of said blade element for movement therewith, said handle being pivoted upon said blade element to permit rotative movement thereof in a plane at right angles to the direction in which the same is moved for operation of said blade element, a latch pivotally mounted upon the free end of said blade element, and a stationary catch to be engaged by said latch for locking of said blade element when the same is moved into circuit closing position, said latch being releasable from said catch by rotative movement of said handle, and said handle and said latch being statically balanced upon their associated pivots to insure against release of said latch from said catch under the action of accelerating forces caused by shock.

2. A shock-proof knife switch comprising a blade element pivoted at one end, a latch pivotally mounted upon the free end of said blade element, a stationary catch to be engaged by said latch for locking of said blade element when the same is moved into circuit closing position, a front operating handle mounted upon the free end of said blade element for movement therewith, said handle being pivoted upon said blade element to permit rotative movement thereof in a plane at right angles to the direction in which the same is moved for operation of said blade element, and a cam associated with said operating handle for releasing said latch upon rotative movement of said handle, said handle and said latch being statically balanced upon their associated pivots to insure against release of said latch from said catch under the action of accelerating forces caused by shock.

3. The combination with a knife switch including movable conducting blades pivoted at one end and having a tie bar extending between

the free ends thereof, of a stationary locking part, a latch mounted upon said tie bar to move therewith and adapted to engage said locking part to lock said blades in circuit closing position, said latch being pivoted upon said tie bar to permit release thereof from said locking part, a spring associated with said latch for yieldingly maintaining the same in locking engagement with said locking part, and a switch operating handle carried by said tie bar and pivoted thereon to permit rotative movement thereof, said latch being releasable from said locking part by rotative movement of said operating handle, and said latch and said handle being statically balanced upon their associated pivots to insure against release of said latch from said locking part under the action of accelerating forces caused by shock.

4. The combination with a knife switch including conducting blades pivoted at one end and having a tie bar extending between the free ends thereof, of a stationary locking part, a spring biased pivoted latch mounted upon said tie bar to move therewith and adapted to engage said locking part to lock said blades in circuit closing position, and a switch operating handle carried by said tie bar and pivoted thereon to permit rotative movement thereof, said operating handle having a cam associated therewith which cooperates with said latch to normally maintain said operating handle in a given angular position and which also acts upon rotative movement of said operating handle out of said normal position to effect release of said latch from said locking part, said operating handle and said latch being statically balanced upon their associated pivots to insure against release of said latch from said locking part under the action of accelerating forces caused by shock.
